HOISTING MECHANISM FOR REMOVING A
CONTAINER FROM A BASEMENT

Paul J. Hanby, Dayton, Ohio

Application August 12, 1947, Serial No. 768,138

18 Claims. (Cl. 214—95)

1

This invention relates to a hoisting mechanism for removing a container from a basement.

One object of the invention is to provide a simple easily operated mechanism for hoisting a loaded container to an elevated point for removal, such as the window of a basement room.

A further object of the invention is to provide an apparatus by which a basket of wet clothes may be easily elevated to and moved into a window of a basement, thus avoiding the necessity of the laundress carrying the heavy load up the basement stairs.

A further object of the invention is to provide such a mechanism which can be manually operated with relatively little effort.

A further object of the invention is to provide such an apparatus in which the load supporting device is so counterbalanced that it can be easily moved in either direction.

A further object of the invention is to provide such a device of a compact construction which can be installed in a relatively small space.

A further object of the invention is to provide such an apparatus of a simple construction which can be manufactured and installed at low cost.

Other objects of the invention may appear as the mechanism is described in detail.

In the accompanying drawings Fig. 1 is a front elevation, partly broken away, of a mechanism embodying the invention; Fig. 2 is a side elevation of such a mechanism; Fig. 3 is a side elevation, on a larger scale, of a portion of such a mechanism; Fig. 4 is a sectional detail on the line 4—4 of Fig. 1; Fig. 5 is a top plan view of one of the supporting devices for the load supporting member; Fig. 6 is a detail view of one of the supporting arms; Fig. 7 is a top plan view of portions of the cables and the pulleys therefore; Fig. 8 is a top plan view of a modified form of the load supporting device; and Fig. 9 is a transverse section taken on the line 9—9 of Fig. 8.

In these drawings I have illustrated one embodiment of my invention, together with a minor modification thereof, and have shown the same as designed primarily for installation in a domestic laundry, but it is to be understood that the mechanism as a whole, as well as the several parts thereof, may take various forms and may be used for various purposes, without departing from the spirit of the invention.

In the particular embodiment here illustrated, the mechanism comprises an upright structure, or main frame, including two upright members or bars 10 which are preferably rigidly connected one with the other by upper and lower cross bars

2

11 and 12. The upright structure may be mounted in a substantially vertical position in any suitable manner but usually it is spaced a short distance from a wall 13 having therein a window 14 and the upright members are supported on the floor and are secured at their upper ends to the joists of the ceiling of the room. In the arrangement here shown each upright member has at its lower end a bracket 16 in which is mounted a threaded stud 17, the stud being held rigidly in adjusted position by nuts 18. The lower end of the stud 17 is rounded and rests in a substantially semicircular recess 19 in the top surface of a base or foot piece 20. The lower edge of the base rests upon the floor and a central stud 21 extends downwardly from the top wall of the base into a recess 22 in the floor. Thus the base is held against lateral displacement but is free to adjust itself to inequalities in the floor surface. Each upright member is provided near its upper end with aligned apertured lugs 23 through which a rod 24 extends, each rod being connected at its upper end with the joists of the ceiling, as by brackets 25. The brackets may be secured directly to one of the joists or to bars extending between two joists. This method of connection permits a structure of a standard height to be installed in rooms having ceilings of different heights.

A carriage is supported on the upright structure for vertical movement thereon and for fore and aft tilting movement with relation thereto. The carriage and the upright members are provided with cooperating parts to guide the lower portion of the carriage in a vertical path while permitting the carriage to tilt about a transverse axis adjacent the lower end thereof. Preferably the upright members 10 are in the nature of channel bars the flanges of which constitute guideways. In the present arrangement the channels are opposed one to the other and one flange of each channel is bent inwardly as shown at 26. The carriage may take various forms and is here shown as a substantially rectangular frame 27 of a length greater than the distance between the upright structure and the wall. The lower end portion of the carriage extends between the upright bars and is provided at its opposite sides with guide members extending into the respective channels. In the arrangement shown aligned studs 28 mounted on respective side members of the carriage extend laterally therefrom into the respective channels, where each stud supports a roller 29 of a diameter slightly less than the width of the channel. The carriage is movably supported by cables 30 and 31, each of which is connected

at one end with the corresponding pivot pin 28. The cables extend upwardly along the bars 10 and about sheaves 32 and 33, then downwardly about other sheaves 34 and 35 and are connected at their other ends with counterbalancing means such as a weight 36. The sheaves may be supported in any suitable manner but are preferably mounted on a bar 36a which forms a part of the upright structure.

Supported on the upper portion of the carriage is a load supporting device 37 which is here shown as a container but which may be merely a support for a container. As the carriage moves upwardly the upper portions thereof and the load supporting device are deflected rearwardly by the pivotal movement of the carriage about the common axis of the pivot pins 28. Means are provided for limiting the tilting movement of the carriage and for guiding the upper end thereof in a predetermined path. In the present arrangement inclined tracks 38 are secured to the upright bars 10 and extend upwardly and rearwardly therefrom to the wall 13. As here shown the upper ends of the tracks are spaced some distance from the lower edge of the window 14 but the tracks may terminate in any desired relation to that opening. The upper end of the carriage is provided with means for movably supporting the same on the tracks, this means preferably comprising rollers 39 which are mounted on the upper end portions of the respective side members 27a of the carriage by pins 40. The arrangement of the load supporting device is such that the weight of the load tends to tilt the carriage towards the tracks 38 and the tracks are so arranged that the carriage will be slightly so tilted when it is in its lowermost position, and the upper portion of the carriage will be slightly to the rear of the vertical plane of the transverse axis about which the carriage moves.

The load supporting device may be mounted on the carriage in any suitable manner but preferably it is mounted on arms 41 which in turn are pivotally mounted on and extend forwardly from the respective pins 40 which carry the rollers 39. The rear portion of each arm 41 is arranged between the roller 39 and the side member of the carriage 27 and the forward portion 41a of the arm is laterally offset from the rear portion thereof toward the load supporting device, thus providing between the two parts a shoulder 42 which engages the side member of the carriage and normally supports the arm in a fixed angular position with relation to the carriage, which in the present instance, is a right angle position. When, as in the present instance, the load supporting device is itself a container or basket, it is desirable that it should be removably mounted on the arms of the carriage and in the arrangement shown studs or pintles 43 are secured to and project laterally from the upper portion of the load supporting device, approximately midway between the front and rear ends thereof, and are supported in open slots 44 in the forward ends of the respective arms. The rear ends of the slots are substantially circular to form bearings for the pintle and thus permit the load supporting device to remain in a horizontal position as the positions of the arms change.

Suitable means are provided for retaining the carriage normally in its lowermost position and as here shown the retaining means comprises a spring pressed pin 45 carried by the lower transverse member 45 of the carriage 12 and a keeper 47 on the transverse member 12 of the upright

structure. When the load is to be hoisted the latch pin 45 is withdrawn from the keeper and if the load on the carriage is such that the counterweight will overbalance the same the carriage will be moved upwardly by the weight. If the load overbalances the counterweight a slight upward pressure on the load supporting device or the carriage will be sufficient to impart upward movement to the carriage and its load. The lower portion of the carriage moves vertically on the upright members 10 but the weight of the load holds the rollers 39 in contact with the tracks 38 and the upper end of the carriage and the load supporting device follow those tracks until the rollers engage the wall 13. The rollers then move upwardly on the vertical surface of the wall and the load supporting device moves in a vertical path until the rollers reach the window opening and enter the same. The rollers will enter the window opening shortly before the carriage moves to a horizontal position and the movement of the carriage to that horizontal position will cause the rollers to move outwardly over the windowsill and move the load supporting device into the window. It is desirable that the load supporting device should be moved to a position in which it projects beyond the outer side of the window so that either the load supporting device itself or the container thereon may be easily removed from the exterior of the building. To accomplish this further movement the upper portions of the shoulders 42 on the arms 41 are inclined slightly so that when the carriage moves to a horizontal position and the arms move to upright positions the weight of the load thereon will move the arms rearwardly about their axes until the inclined surfaces of the arms contact the side members of the carriage, thus moving the arms, and therefore the load outwardly with relation to the window to the position shown at 41b, in Fig. 2. A light spring 51 is connected with the arm 41a and with the carriage to return the arm to its normal position when the carriage is moved toward its initial position. The carriage may be returned to its initial position as soon as the load has been removed therefrom but it may remain in its elevated position until the basket has been filled with dry clothes and replaced on the carriage. Usually the counterweights will be such as to retain the carriage in its elevated position until a downward pull is exerted thereon. A very light pull will be sufficient to restore the carriage to its initial position.

In Figs. 8 and 9 there is shown a modified form of a load supporting device, in which the device comprises a platform 48 having at its ends upwardly extending parts 49 provided with pintles 40 to enter the slots in the supporting arms 41. Thus any suitable container may be placed on and removed from the platform.

While I have shown and described one embodiment of my invention, together with a minor modification thereof, I wish it to be understood that I do not desire to be limited to the details thereof as various modifications may occur to a person skilled in the art.

Having now fully described my invention what I claim as new and desire to secure by Letters Patent is:

1. A mechanism for hoisting a load to an opening in a wall comprising an upright structure adapted to be mounted adjacent said wall, a carriage supported adjacent its lower end on said structure for vertical movement thereon throughout its travel and for tilting movement

with relation thereto about an axis adjacent said lower end thereof, a load supporting device on said carriage tending to tilt the same toward said wall as said carriage moves upwardly, and means to control the tilting of said carriage and guide the same towards said opening.

2. A mechanism for hoisting a load to an opening in a wall comprising an upright structure adapted to be mounted adjacent said wall, a carriage supported adjacent its lower end on said structure for vertical movement thereon throughout its travel and for tilting movement with relation thereto about an axis adjacent said lower end thereof, a load supporting device on said carriage tending to tilt the same toward said wall as said carriage moves upwardly, an inclined track extending from said upright structure to said wall, and a member connected with said carriage and moving on said track to control the tilting of said carriage, whereby the upward movement of said carriage causes said member to move on said track and said wall to said opening.

3. A mechanism for hoisting a load to an opening in a wall comprising an upright structure adapted to be mounted adjacent said wall, a carriage supported adjacent its lower end on said structure for vertical movement thereon throughout its travel and for tilting movement with relation thereto about an axis adjacent said lower end thereof, a load supporting device on said carriage tending to tilt the same toward said wall as said carriage moves upwardly, an inclined track extending from said upright structure to said wall, a member connected with said carriage and moving on said track to control the tilting of said carriage and guide said load supporting device into said opening, and means for moving said load supporting device outwardly with relation to said carriage when the latter has reached the limit of its upward movement.

4. A mechanism for hoisting a load to an opening in a wall comprising an upright structure adapted to be mounted adjacent said wall, a carriage supported adjacent its lower end on said structure for vertical movement thereon throughout its travel and for tilting movement with relation thereto about an axis adjacent said lower end thereof, inclined guideways extending from said upright structure to said wall, arms pivotally mounted on said carriage, a load supporting device carried by said arms, rollers carried by the upper portion of said carriage and engaging said guides to control the tilting of said carriage, said arms having means whereby they will be released for forward pivotal movement with relation to said carriage when said load supporting device is moved into said opening.

5. In a load hoisting mechanism, an upright structure, a carriage, means for supporting said carriage for vertical movement on said structure throughout its travel, the upper portion of said carriage being movable transversely to the lower portion thereof, a load supporting device on said upper portion of said carriage and means controlled by the vertical movement of said carriage for imparting transverse movement to said upper portion thereof.

6. In a load hoisting mechanism, an upright structure, a carriage supported for vertical movement on said structure and for fore and aft tilting movement with relation thereto about an axis adjacent the lower end of said carriage, a load supporting device mounted on the upper

portion of said carriage and tending to tilt the latter rearwardly and means for controlling the tilting of said carriage by said load supporting device and causing the latter to move upwardly and rearwardly as said carriage moves upwardly.

7. In a load hoisting mechanism, an upright structure, a carriage supported for vertical movement on said structure and for fore and aft tilting movement with relation thereto about an axis adjacent the lower end of said carriage, the upper end of said carriage being in the rear of the vertical plane of said axis when said carriage is in its lowermost position, a load supporting device mounted on said upper portion of said carriage, and means to control the rearward tilting movement of said carriage and to cause said load supporting device to move rearwardly as it moves upwardly with said carriage.

8. In a load hoisting mechanism, an upright structure, an inclined guide extending upwardly and rearwardly from the lower portion of said structure, a carriage supported for vertical movement on said structure to a position above the lower end of said guide and for fore and aft tilting movement with relation thereto about an axis adjacent the lower end of said carriage, and a load supporting device on the upper portion of said carriage, said carriage having a part movable on said guide to control the tilting movement of said carriage.

9. In a load hoisting mechanism, an upright structure, a carriage supported adjacent its lower end for vertical movement on said structure and for rearward tilting movement about a transverse axis with relation to said structure, means controlled by the upward movement of said carriage for causing the upper portion thereof to move both upwardly and rearwardly while the lower portion thereof moves vertically, and means supporting a load on said upper portion of said carriage.

10. In a load hoisting mechanism, an upright structure, a carriage supported adjacent its lower end for vertical movement on said structure and for rearward tilting movement about a transverse axis with relation to said structure, means for supporting the upper end of said carriage normally in the rear of the vertical plane of said axis and guiding the same in an upwardly inclined path, and means for supporting a load on said upper end of said carriage.

11. In a load hoisting mechanism, an upright structure, a carriage supported adjacent its lower end for vertical movement on said structure and for rearward tilting movement about a transverse axis with relation to said structure, means for guiding the upper portion of said carriage in an upwardly inclined path while the lower portion thereof moves vertically, and means for supporting a load on said upper portion of said carriage and for biasing the latter toward said guiding means.

12. In a load hoisting mechanism, an upright structure, a carriage, supported adjacent its lower end for vertical movement on said structure and for rearward tilting movement about a transverse axis with relation to said structure, means controlled by the upward movement of said carriage for causing the upper portion thereof to move both upwardly and rearwardly, arms pivotally mounted on said upper portion of said carriage and retained normally in fixed positions with relation thereto, a load supporting device carried by said arms, and means for releasing said arms for forward movement with rela

to said carriage when the latter is in its uppermost position.

13. In a load hoisting mechanism, an upright structure, a carriage supported adjacent its lower end for vertical movement on said structure and for rearward tilting movement about a transverse axis with relation to said structure, means controlled by the upward movement of said carriage for causing the upper portion thereof to move both upwardly and rearwardly, means supporting a load on said upper portion of said carriage, and means for counterbalancing the weight of said carriage and the load thereon.

14. In a load supporting mechanism, a structure comprising upright members having substantially parallel guideways, guide members movable in said guideways, a relatively short frame pivotally mounted adjacent its lower end on said guide members, an inclined track extending upwardly and rearwardly from said structure, means for movably supporting the upper portion of said frame on said track, and a load supporting device on said upper portion of said frame.

15. In a load supporting mechanism, a structure comprising upright members having substantially parallel guideways, guide members movable in said guideways, a relatively short frame pivotally mounted adjacent its lower end on said guide members, inclined tracks extending upwardly and rearwardly from said structure, means for movably supporting the upper portion of said frame on said track, a load supporting device on said upper portion of said frame, sheaves on the upper portion of said structure, cables connected with the respective guide members and extending about said sheaves, and a counterbalancing weight connected with said cables.

16. In a load supporting mechanism, a structure comprising upright members having substantially parallel guideways, guide members movable in said guideways, a relatively short frame pivotally mounted adjacent its lower end on said guide members, an inclined track extending upwardly and rearwardly from said structure, means for movably supporting the upper portion of said frame on said track, a load supporting device on said upper portion of said frame, sheaves on the upper portion of said structure, cables connected with the respective guide members and extending about said sheaves, a counterbalancing weight connected with said cables, and shock absorbing means connected with said weight.

17. In a load hoisting mechanism, an upright structure comprising substantially parallel bars, having opposed longitudinal channels, a relatively short frame the lower portion of which extends between said bars, pivot pins in the respective sides of said frame, rollers on said pivot pins within the respective channels, upwardly inclined tracks connected with said bars, arms supported on and extending forwardly from the upper portion of said frame, a load supporting device on the forward end portions of said arms and rollers supporting said upper portions of said frame on said tracks.

18. In a load hoisting mechanism, an upright structure comprising substantially parallel bars, having opposed longitudinal channels, a relatively short frame the lower portion of which extends between said bars, pivot pins in the respective sides of said frame, rollers on said pivot pins within the respective channels, upwardly inclined tracks connected with said bars, rollers supporting the upper portion of said frame on said tracks, arms pivotally supported on said upper portion of said frame and extending forwardly at substantially right angles thereto, and a load supporting device on the forward end portions of said arms, said arms being movable rearwardly about their axes when said frame is in a substantially horizontal position.
